UNITED STATES PATENT OFFICE.

BERNARD FRESE, OF LEMOORE, CALIFORNIA, ASSIGNOR TO JACOB COMBS, OF LEMOORE, CALIFORNIA.

OIL-BURNER.

1,183,550.

Specification of Letters Patent. Patented May 16, 1916.

Application filed July 29, 1915. Serial No. 42,495.

To all whom it may concern:

Be it known that I, BERNARD FRESE, a citizen of the United States, residing at Lemoore, in the county of Kings and State 5 of California, have invented certain new and useful Improvements in Oil-Burners, of which the following is a specification.

My invention relates to improvements in oil burners, and is an improvement upon the 10 oil burner for which patent was granted to me, December 1, 1914, Number 1,119,591.

One object of my invention is the provision of an oil burner where petroleum or distillates thereof are converted into gas before ignition takes place. The gas generated in the known burners of this kind, is under more or less pressure which causes the carbon residue in the heated generator to become hard, and causes the small openings, from which the gas escapes to clog 20 and gradually close.

Another object of my invention is the provision of an oil burner which eliminates these objections by producing a gas generator that allows the gas to escape freely therefrom without the gas becoming ignited therein. The advantage I obtain 25 thereby is that the sediment formed in the generator does not harden, but is of a soft 30 spongy consistence easily removed, and allows the gas to expand before being ignited.

Another object of my invention is the provision of an oil burner in which the oil is superheated and converted into gas before entering the generator.

Another object of my invention is the provision of an oil burner in which the mixture of air with the gas produces a perfect combustion thereby being economical in 40 fuel.

Another object of my invention is the provision of an oil burner for the purposes stated, which will be inexpensive to manufacture, simple of construction, durable and 45 practical from every point of view.

With these objects in view my invention consists of an oil burner embodying novel features of construction and combination of parts for service substantially as shown, described, and particularly defined by the 50 claims.

Figure 1 is a perspective view of a burner constructed in accordance with and embodying my invention. Fig. 2 is a central sec-

tional view, and Fig. 3 is a detail view of 55 the distributor or burner head.

In the drawings in which similar letters denote similar parts throughout the several views, the letter A, designates the casting having the lug receiving openings B, to receive the lugs C of the tapered burner head or distributor D, projecting into the mouth or opening E, of the combustion chamber F, of the casting. Integral with the casting A, is the oil conductor G, having the threaded end H, to receive the oil feed, and the threaded end H', receiving the threaded end J of the pipe J'. Attached to the pipe J' is the elbow K receiving the vertical pipe L, which pipe is in the path of the flame, thereby causing the oil to be superheated and converted into gas. Connected to the top of the pipe L is the elbow M, leading from 60 which is the horizontal pipe N, connected to the pipe N', by the union O.

The wedge-shaped burner head or distributor D, has the two threaded openings P, in order that the interior of the distributor may be cleaned, said openings being closed by the threaded plugs P', and the distributor is further provided with a threaded opening Q, in its top to receive the nipple elbow Q', connected to the pipe N'. Thus it will be readily seen that the oil enters the conductor G at H, thence through the pipe 65 J', into the vertical pipe L, where it is converted into gas by the heat from the flames. The gas then passes through the horizontal pipe and through the nipple elbow Q', into 70 the distributor. The distributor D has its 75 inner end tapered and has the slot opening R, through which the gas passes into the chamber F in a spray.

From the foregoing description taken in 80 connection with the drawings the operation 85 of my oil burner will be readily understood, and it will be apparent that the oil is fed to the conductor on the underside of the casting, thence through the heating pipe 90 where it is subjected to great heat and converted into a vaporous gas, and is then fed to the distributor or burner head and into the generating chamber of the casting, drawing in sufficient air to produce a highly 95 inflammable gas which is ignited at the 100 proper location to insure the highest degree 105 of efficiency.

It will be noted that the several parts of

the burner are easily accessible for the purpose of cleaning, removal or repair; also that the construction is simple, strong and durable; inexpensive of production and absolutely reliable, efficient and practical.

I claim:

1. An oil burner, consisting of a casting provided with an oil supply channel and mixing chamber, an oil heating and conducting pipe leading from said oil supply channel, said conducting pipe passing through the path of the flame, whereby the oil is converted into a vaporous gas by the intense heat, said casting being provided at its mouth with recesses, and a burner head or distributor connected to said pipe and provided with lugs engaging said recesses for securing said burner head in proper relation.
2. An oil burner, consisting of a casting provided with an oil supply channel and

mixing chamber, an oil heating and conducting pipe leading from said oil supply channel, said conducting pipe passing through the path of the flame, whereby the oil is converted into a vaporous gas by the intense heat, said casting being provided at its mouth with recesses, and a burner head or distributor connected to said pipe and provided with lugs engaging said recesses for securing said burner head in proper relation, said burner head having its ends formed with openings provided with removable plugs and an air opening surrounding said burner head to allow the entrance of air.

In testimony whereof I affix my signature in the presence of two witnesses.

BERNARD FRESE.
